(57) **CLAIM**

The ornamental design for a wafer holder for manufacturing semiconductor, as shown and described.

DESCRIPTION

FIG. 1 is a front view of a wafer holder for manufacturing semiconductor showing our new design;
FIG. 2 is a rear view thereof;
FIG. 3 is a top plan view thereof;
FIG. 4 is a bottom plan view thereof;
FIG. 5 is a right side view thereof;
FIG. 6 is a left side view thereof;
FIG. 7 is a front perspective view thereof;
FIG. 8 is an enlarged cross sectional view taken along line 8-8 in FIG. 1;
FIG. 9 is an enlarged portion view taken along line 9-9 in FIG. 1; and,
FIG. 10 is another front perspective view of FIG. 1 shown in a used condition with wafers shown in broken lines.
The features shown in dotted lines depict environmental subject matter only and form no part of the claimed design.
